CLAIM

The ornamental design for a bumper pet toy, as shown and described.

DESCRIPTION

FIG. 1 is a front, right perspective view of a bumper pet toy according to the present invention;

FIG. 2 is a front view of the bumper pet toy shown in FIG. 1, which is the same as the top, bottom, and rear views due to the symmetry of the design; and,

FIG. 3 is a right side view of the bumper pet toy shown in FIG. 1, which is the same as a left side view due to the symmetry of the design.

1 Claim, 1 Drawing Sheet
